Primary Examiner — Lakiya Rogers*Assistant Examiner* — Rhea Shields(74) *Attorney, Agent, or Firm* — Ladas & Parry LLP(57) **CLAIM**

The ornamental design for a display screen or portion thereof with icon, as shown and described.

DESCRIPTION

FIG. 1 is a front view of a display screen or portion thereof with icon showing our new design;

FIG. 2 is a front view thereof, in which a display panel and graphical user interface in broken lines is provided to illustrate an example environment.

The dash-dot broken line illustrates portions of the display screen while the even broken line showing within the dash-dot broken lines illustrate portions of the icon. In FIG. 2, the broken lines surrounding the dash-dot lines showing a full display screen and graphical user interface is provided for the purposes of illustrating environmental structure. No subject matter shown in either the dash-dot broken lines or even broken lines form part of the claimed design.
